UNITED STATES PATENT OFFICE.

GEORGES CLAUDE, OF PARIS, FRANCE, ASSIGNEE TO SOCIETE L'AIR LIQUIDE (SOCIETE ANONYME POUR L'ETUDES ET L'EXPLOITATION DES PROCEDES GEORGES CLAUDE), OF PARIS, FRANCE.

COMPOSITION FOR FORMING EXPLOSIVES WITH LIQUID OXYGEN.

1,111,247.

Specification of Letters Patent. Patented Sept. 22, 1914.

No Drawing.

Application filed January 25, 1913. Serial No. 744,237.

To all whom it may concern:

Be it known that I, GEORGES CLAUDE, a citizen of the Republic of France, residing at 48 Rue St. Lazare, Paris, in the Republic of France, have invented certain new and useful Improvements in Compositions for Forming Explosives with Liquid Oxygen, of which the following is a specification.

This invention relates to compositions for forming explosives and has particular reference to blasting material of the kind in which powdered aluminium or a similarly-acting metallic substance is used in conjunction with liquid oxygen.

According to the present invention the composition with which the liquid oxygen is used is composed of powdered aluminium or a similarly-acting metallic substance, presenting the same great advantage of yielding innocuous products of combustion, mixed with a suitable inert material, the proportion being such that, in the case of aluminium, each liter of the composition contains from one hundred to six hundred grams of the aluminium. As the inert material, which should also be light, silica, infusorial earth (kieselguhr), or light metallic oxids, alumina for example, may be used. In place of powdered aluminium a chemically equivalent amount of any other combustible metal or compound having innocuous products of combustion may be employed, as for example a metallic silicid or hydrid, calcium hydrid for example.

The composition may be shaped into cartridges and stored in bags of canvas or other porous material and be furnished with an igniting device of any appropriate kind, for example a fusible wire, alone or associated with a detonating substance such as fulminate. When it is desired to use a cartridge, it is immersed in liquid oxygen for some time, and then taken out of the liquid and placed in position for instance in a hole in the rock to be blasted. It affords sufficient time for placing in position, and the flight of the operator into safety.

In order to lengthen the interval available between the time of placing the cartridge in position and the instant of its explosion, which interval is about five minutes in the case of cartridges weighing two hundred grams, a heat-insulating sheath may be provided for each bag; this sheath may consti-

tute a double or jacketed envelop with an empty space between its inner and outer walls, or may consist of asbestos or other suitable absorbent material, which becomes impregnated with the liquid oxygen into which the whole is dipped just prior to use and thereby constitutes for the first few minutes a protection for the cartridge proper against the penetration of heat.

The composition above described is distinguished by several important features. The efficacy of the composition is due to the vaporizing and sudden expanding effect of the heat of combustion upon the excess of liquid oxygen that it contains. Owing to the choice of the substances used there is an absence of noxious or offensive products of the combustion and these products are solid at ordinary temperatures. The high explosive power of the composition when impregnated with liquid oxygen is due to the fact that, notwithstanding the relatively small quantity of combustible, the latter is uniformly disseminated in sufficient quantity throughout the whole mass owing to the inert material acting as a diluent, with the result that at each point there is a production of the exact quantity of heat necessary for the full explosive action, whereas otherwise the explosive action would take place in two stages, one being the production of the heat and the other the transmission of this heat to the excess of liquid oxygen, thereby greatly impairing the violence of the action.

It will be understood that, as liquid oxygen evaporates after a short time, the risk of misfires is eliminated; also the composition can be stored with safety, because the solid products of which it is composed are inert of themselves and do not need to be mixed or impregnated with liquid oxygen until just prior to use.

What I claim and desire to secure by Letters Patent of the United States is:—

1. A composition for forming explosives with liquid oxygen, comprising a combustible metallic substance yielding by oxidation innocuous products of combustion, and a light inert substance acting as a solid diluent, the amount of the metallic substance in one liter of the composition being chemically equivalent to from one to six hundred grams of powdered aluminium.

2. A composition for forming explosives with liquid oxygen, comprising a combustible metal in powder form, and a light inert substance acting as a solid diluent, the amount of the powdered metal in one liter of the composition being chemically equivalent to from one to six hundred grams of powdered aluminium. 50
3. A composition for forming explosives with liquid oxygen, comprising powdered aluminium, and a light inert solid substance acting as a diluent, these constituents being in the proportion of from one hundred to six hundred grams of the powdered metal to each liter of the mixture. 55
4. A composition for forming explosives with liquid oxygen, comprising powdered aluminium, and a light inert solid substance acting as a diluent, these constituents being in the proportion of from one hundred to six hundred grams of the powdered metal to each liter of the mixture, and means for provoking the ignition of the composition. 60
5. A composition for forming explosives with liquid oxygen, comprising a combustible metallic substance yielding by oxidation innocuous products of combustion, and a light inert substance acting as a solid diluent, the amount of the metallic substance in one liter of the composition being chemically equivalent to from one to six hundred grams of powdered aluminium, and a porous bag surrounding the composition to form it into a cartridge. 65
6. A composition for forming explosives with liquid oxygen, comprising powdered aluminium, and a light inert solid substance, these constituents being in the proportion of from one hundred to six hundred grams of the powdered metal to each liter of the mixture, and a porous bag surrounding the composition to form it into a cartridge. 70
7. A composition for forming explosives with liquid oxygen, comprising a combustible metallic substance yielding by oxidation 75

innocuous products of combustion, and a light inert substance acting as a solid diluent, the amount of the metallic substance in one liter of the composition being chemically equivalent to from one to six hundred grams of powdered aluminium, a porous bag surrounding the composition to form it into a cartridge, and a heat insulating sheath enveloping the bag.

8. A composition for forming explosives with liquid oxygen, comprising powdered aluminium, and a light inert solid substance, these constituents being in the proportion of from one hundred to six hundred grams of the powdered metal to each liter of the mixture, a bag surrounding the composition to form it into a cartridge, and a heat insulating sheath enveloping the bag. 80

9. A composition for forming explosives with liquid oxygen, comprising a combustible metallic substance yielding by oxidation 85

innocuous products of combustion, and a light inert substance, acting as a solid diluent, the amount of the metallic substance in one liter of the composition being chemically equivalent to from one to six hundred grams of powdered aluminium, a bag surrounding the composition to form it into a cartridge, and an asbestos sheath enveloping the bag. 90

10. A composition for forming explosives with liquid oxygen, comprising powdered aluminium, and a light inert solid substance, 95

these constituents being in the proportion of from one hundred to six hundred grams of the powdered metal to each liter of the mixture, a bag surrounding the composition to form it into a cartridge, and an asbestos sheath enveloping the bag. 100

In testimony whereof I affix my signature 85
in presence of two witnesses.

GEORGES CLAUDE.
